Company, a corporation of Delaware

Filed June 27, 1960, Ser. No. 61,129

Term of patent 14 years

(Cl. D26—1)

FIG. 1 is a side elevational view of an alternating current split-core ammeter, showing our new design, the opposite side being substantially a mirror image thereof;

FIG. 2 is a bottom plan view;

FIG. 3 is a front elevational view; and

FIG. 4 is a rear elevational view thereof.

A portion of FIG. 1 is diagonally lined to indicate transparency.

We claim:

The ornamental design for an alternating current split-core ammeter, as shown and described.
